United States Patent Office

Des. 205,858
Patented Sept. 27, 1966

205,858

LAMP

Leo H. Klausen, 338 Hillcrest Ave., Willowdale,
Ontario, Canada

Filed Aug. 2, 1965, Ser. No. 86,403

Term of patent 14 years

(Cl. D48—18)

FIG. 1

FIG. 2

FIG. 4

FIG. 3

FIG. 5

FIGURE 1 is a perspective view of a lamp showing my new design, the undisclosed sides being similar in appearance;

I claim:

The ornamental design for a lamp, as shown and described.
